GAS-DISCHARGE TUBE FOR HIGH-CURRENT PULSED OPERATION

The present invention provides a form of gas-discharge tube suitable for use in the generation of short current pulses at high repetition rate by the repeated striking and extinction of a cold-cathode arc. This class of arc is obtainable when using as cathode a metal whose thermionic emission capability at and below its boiling-point is insufficient to provide the current density observed in the arc. The arc is localised at a very small area of the cathode surface, the position of this area varying with time, and immediately above the surface at the arc site is a dense cloud of vapour of the cathode metal confined at high pressure by momentum transfer from incident positive ions.

According to the invention there is provided a gas-discharge tube having an anode and an unheated metal cathode between which a cold-cathode arc may be struck by the application of a suitable voltage between them, that part of the surface of the cathode which is exposed to the gas-filling of the tube bounding at least one cavity in the cathode such that for at least a majority of points on said part of the surface the outward normal to the surface intersects said part of the surface at a distance not exceeding 5 millimetres and preferably not exceeding 2 millimetres.

Preferably the cathode forms part of the envelope of the tube.

It would appear that the merit of the form of cathode structure used in a tube according to the invention resides in enabling the anode voltage, following extinction of the arc, to be raised rapidly to its original level without premature restriking of the arc. It is thought that the ability of the discharge gap of a cold-cathode arc device to recover in this way is dependent on rapid dispersal of the cloud of cathode-metal vapour formed in the arc and that this is achieved in the present case by the provision of a condensation surface forming part of the cathode within close range of the majority of possible arc sites.

One arrangement in accordance with the invention will now be described by way of example with reference to the accompanying drawings in which:

FIG. 1 is a diagrammatic sectional view of the basic construction of a discharge tube embodying the invention;

FIG. 2 is an outline circuit diagram of a relaxation oscillator illustrating the use of the tube in controlling the delivery of current pulses to a load; and

FIGS. 3a and 3b are diagrams illustrating voltage and current waveforms for the tube.

Referring to FIG. 1, the tube comprises a sealed envelope filled with a gas at a pressure about 0.5 Torr, the envelope comprising co-axial ceramic tubes 1 and 2 each 25 mm in length and diameter and having a wall thickness of 3 mm. The nature of the gas filling is not critical, but it is convenient to use hydrogen since this lends itself readily to pressure stabilisation using well known replenisher techniques. The remote ends of the tubes 1 and 2 are respectively sealed by metal plates 3 and 4 and the open ends are spaced axially by a gap 7 of width 1 mm, the tubes being sealed adjacent these ends to an external copper ring 5. The ring 5 has a circumferential slit 6 of depth 5 mm extending from its inner face, the slit 6 having the same width as and being aligned with the gap 7 between the ceramic tubes 1 and

2. The tube is operated with the ring 5 as cathode and one of the plates 3 and 4 as anode.

Referring to FIG. 2, the tube 8 is connected in series with an inductor 9 across a high voltage d.c. source 10, that one of the plates 3 and 4 not serving as anode being left floating. Across the tube 8 are connected in series a load 11, an inductor 12 and a capacitor 13.

The operation of the circuit for each cycle is as follows, starting from the point immediately after the passage of a current pulse through the load 11. At this point the voltage across the capacitor 13 is relatively low and the capacitor 13 charges from the source 10 via the inductors 9 and 12 and the load 11. The inductor 9 is arranged to have a very much larger impedance than either the inductor 12 or the load 11 so that the time constant for charging the capacitor 13 is primarily determined by the value of the inductor 9 and the capacitor 13.

Depending on the initial value of the capacitor voltage, a residual low-current glow discharge may exist in the tube 8, but in any event such a discharge will form as the capacitor 13 charges, this discharge being maintained by current drawn from the source 10.

As the capacitor voltage is further increased the tube current also increases in the abnormal glow regime until at about 2,000 volts there is an abrupt transition to an arc regime capable of supporting a high current with only a small voltage drop. The required current cannot be derived from the source 10 because of the presence of the inductor 9 and hence the capacitor 13 begins to discharge through the tube 8, the load 11 and the inductor 12. In consequence a large pulse of current passes through the load 11, the duration of this pulse being determined by the time constant of the capacitor 13 and the inductor 12.

FIG. 3a shows the variation of the tube voltage with time, rising to the arc transition level V_t and abruptly falling to the arc maintenance level V_A . The corresponding change in current is as shown in FIG. 3b. As the current pulse decays to a low value the arc ceases to be self-sustaining and the discharge may extinguish completely or may revert to a low current glow maintained by current drawn from the source 10. Dependent on the extinction condition for the arc a voltage indicated by V_C in FIG. 3a will remain on capacitor 13.

Capacitor 13 will then recharge and the process will be repeated cyclically with a periodic time T and a pulse length t , as indicated in FIGS. 3a and 3b provided that T is made several times as large as t . The amplitude of the current pulse may be controlled according to the value of the capacitor 13 so that a suitable combination of pulse characteristic and periodic time may be chosen to determine the mean power delivered to the load 11.

While a series resonant arrangement is shown in FIG. 2 other known arrangements (e.g., a parallel resonant arrangement) would be equally effective.

As has been described, the instant of initiation of the arc is determined by the charging of capacitor 13 to the transition voltage V_t . In order to obtain great precision in the timing of the initiation of the arc it is possible in a modification of the arrangement described above, to operate as a trigger electrode that one of the plates 3 and 4 not serving as anode. In this mode of operation, at a time when capacitor 13 is approaching the transition voltage V_t , a voltage pulse sufficient to ensure the

striking of an arc is applied to the trigger electrode. The discharge will then immediately transfer to the main gap. Alternatively the trigger pulse may be injected into the supply at a point between the source 10 and the main anode.

An oscillatory circuit as described above has been operated with a pulse duration of less than 1 microsecond at a repetition rate in excess of 100 KHz. The switching rate of the tube is therefore superior to that of a thyratron or thyristor.

In an alternative arrangement using a non-oscillatory circuit single-shot operation is obtained by applying a standing voltage which is insufficient to cause an arc and superimposing a trigger voltage when the arc is to be initiated.

We claim:

1. A gas-discharge tube comprising: a sealed envelope having a gas filling; an anode exposed to the gas filling; and an unheated cathode having only a part of its surface exposed to the gas filling, said cathode being of a metal such that a cold-cathode arc may be struck

between the anode and the cathode by the application of a suitable voltage between them, said only part of the surface of the cathode which is exposed to the gas filling consisting of at least one cavity in the cathode such that for at least a majority of points on said part of the surface the outward normal to the surface intersects said part of the surface at a distance not exceeding 5 millimeters.

2. A gas-discharge tube according to claim 1 in which for at least a majority of points on said part of the surface the outward normal to the surface intersects said part of the surface at a distance not exceeding two millimeters.

3. A gas-discharge tube according to claim 1 in which said part of the surface of the cathode is the surface of an annular slit.

4. A gas-discharge tube according to claim 1 in which the cathode material is copper.

5. A gas-discharge tube according to claim 1 in which the cathode forms part of the envelope of the tube.
